F. J. REMMLEIN,

STOKER GRATE.

APPLICATION FILED FEB. 2, 1918.

UNITED STATES PATENT OFFICE.

FRANK J. REMMLEIN, OF PHILADELPHIA, PENNSYLVANIA.

STOKER-GRADE.

1,802,221.

Specification of Letters Patent. Patented Apr. 29, 1919.

Application filed February 2, 1918. Serial No. 215,649.

To all whom it may concern:

Be it known that I, FRANK J. REMMLEIN, a citizen of the United States, residing at Philadelphia, in the county of Philadelphia, 5 State of Pennsylvania, have invented a new and useful Stoker-Grate, of which the following is a specification.

My present invention relates to a stoker grate and consists more particularly in a 10 novel construction and arrangement for securing the grate bars with respect to the driving sprocket chain.

It further consists of a novel construction of grate bar and novel means for securing it 15 in position.

Other novel features of construction and advantage will hereinafter more clearly appear in the detailed description of my invention.

20 For the purpose of illustrating my invention, I have shown in the accompanying drawing typical embodiments of it which are at present preferred by me, since these embodiments will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in side elevation, a stoker grate embodying my invention, the 25 sprocket wheel shaft being shown in section.

Fig. 2 represents a section on line 2—2 of Fig. 1.

Fig. 3 represents a section on line 3—3 of Fig. 2.

40 Fig. 4 represents, in perspective, a novel fastening device employed.

Fig. 5 represents a sectional view of another embodiment of my invention.

Similar numerals of reference indicate 45 corresponding parts.

Referring to the drawings:—

1 designates a shaft on which a sprocket wheel 2 is fixed in any desired manner. 3 designates a sprocket chain which is driven 50 by the sprocket wheel 2 in any desired or conventional manner. 4 designates the grate bars which are secured to a link 5 of the sprocket chain. In the preferred embodiment of my invention, the grate bars 4 are 55 cast or formed with the downwardly pro-

jecting lugs 6, see Fig. 3, which are recessed, as indicated at 7, such recesses opening through the bottom of the lugs 6 and being preferably of a polygonal contour. In the form illustrated the walls of the recesses 7 60 are rectangular in order to receive the rectangular shaped head 8 of a fastening device 9 which is provided with a threaded rod or stem 10. The stem 10 passes through a vertically disposed aperture 11 in a grate bar 4 65 and its threaded end extends into the countersunk portion 12 of the grate bar and is provided with nuts 13, one of which serves as a lock nut. The head 8 of the fastening device is provided with an aperture 14 extending through it and through this aperture extends a pin 15 which also passes through a link and is provided with a threaded portion 16 which is in threaded engagement with one of the links. 70

In some cases, the grate bar is made as seen in Fig. 5, in which the lug 17 is formed separate from the grate bar 18, and in practice the lug 17 is usually formed of a drop forging and is connected with the grate bar 18 by means of the pins 19 which are cast in the grate bar 18 when the latter is completed, it being understood that the grate bars are first formed and the pins 19 are passed through the grate bar and screwed 85 into the lugs 17. The metal is then poured in to set the pins in the grate bar, as will be understood by reference to Fig. 5, it being understood that recesses are left in the grate bar until after the pins are in position and 90 then the metal is poured in to finish the grate bar.

It will be apparent that if at any time it is desired to remove a grate bar for any reason, this can be readily accomplished by removing the nuts 13, whereupon the grate bar 4 can be readily removed and a new grate bar secured to the sprocket chains. 95

In the construction illustrated, the grate bars are adapted to overlap each other. It 100 is, however, to be understood that my invention is not limited to any special construction of grate bar and may be employed to advantage in conjunction with any desired or conventional type of grate bar or sprocket 105 chain.

It has been customary in devices of this character as heretofore manufactured to make the lug of a drop forging and secure it to the grate bar. The grate bar is se- 110

cured to the sprocket chain by means of a pin passing laterally therethrough and when it is desired to remove a grate bar, it is necessary to remove the pin. This is a very difficult operation, since the pins become warped and distorted due to the heat and the threads become stripped so that in many cases in practice it is necessary to put the stoker out of commission in order to change 10 the grate bar. My present invention obviates such defects.

It will now be apparent that I have devised a novel and useful stoker grate, which embodies the features of advantage enumerated 15 as desirable in the statement of the invention and the above description, and while I have, in the present instance, shown and described typical embodiments of it which will give in practice satisfactory and reliable results, it is to be understood that these 20 embodiments are susceptible of modification in various particulars without departing from the spirit or scope of the invention or sacrificing any of its advantages.

Having thus described my invention, what I claim as new and desire to secure by Letters Patent, is:—

1. In a device of the character stated, the

combination with grate bars having at their ends bottom lugs with recesses in their under side and provided with apertures communicating with said recesses and countersunk at their upper ends, of fastening devices having heads to seat in said recesses and stems to pass through said apertures, 30 nuts in threaded engagement with said stems, sprocket chains, and pins extending laterally through said sprocket chains and through the heads of said fastening devices. 35

2. In a device of the character stated, the 40 combination with the grate bars having lugs provided with polygonal shaped recesses, of fastening devices having polygonal shaped heads to seat in said recesses and stems passing through said grate bars, means carried by said stems to secure said fastening devices to said grate bars, a sprocket chain, and pins in threaded engagement with said sprocket chain and passing through said heads to secure said heads to said sprocket chain.

FRANK J. REMMLEIN.
